J., A. & J. P. BARKER.

CHAIR ARM.

APPLICATION FILED JUNE 20, 1911.

1,036,421.

Patented Aug. 20, 1912.

UNITED STATES PATENT OFFICE.

JAMES BARKER, ALFRED BARKER, AND JOSEPH P. BARKER, OF PHILADELPHIA,
PENNSYLVANIA, ASSIGNORS TO SAID JAMES BARKER.

CHAIR-ARM.

1,036,421.

Specification of Letters Patent. Patented Aug. 20, 1912.

Application filed June 20, 1911. Serial No. 634,297.

To all whom it may concern:

Be it known that we, JAMES BARKER, ALFRED BARKER, and JOSEPH P. BARKER, citizens of the United States, residing in Philadelphia, county of Philadelphia, State of Pennsylvania, have invented certain Improvements in Chair-Arms, of which the following is a specification.

One object of this invention is to improve 10 the construction of chair arms, particularly those used on barbers' and dentists' chairs.

It is desirable in chairs which are daily occupied by a number of different people, such for instance as barbers' chairs, to make 15 the parts as sanitary as possible. This object we attain by making the body portion of the arm of vitreous material such as china, glass or other equivalent material, so that it can be quickly and readily 20 cleansed.

A further object of the invention is to construct the arm so that the vitreous material will be properly supported and will not be liable to crack or break, due to un- 25 even expansion, or due to the clamping of the glass upon a rigid base.

A still further object of the invention is to make the body of the arm in such a manner that the supporting medium will be 30 hidden from view.

In the accompanying drawings:—Figure 1, is a plan view of a chair arm, illustrating our improvement; Fig. 2 is a longitudinal sectional view on the line 2—2, Fig. 1; 35 Fig. 3, is a transverse sectional view on the line 3—3 Fig. 2; Fig. 4, is a transverse sectional view on the line 4—4 Fig. 2; Fig. 5, is a detached perspective view of the metallic base section upon which the arm is 40 mounted; Fig. 6, is a perspective view of the vitreous body portion; Fig. 7, is a perspective view of the intervening coupling section; Fig. 8, is a view showing the filling block and washer, and Fig. 9, is a sectional view illustrating a modification of 45 the invention.

A is the metallic base having perforated lugs a at each end, which are attached to the moving parts of the chair, as it will be 50 understood that this particular form of base is used in connection with a barber's chair in which the back and foot rests are movable.

B is a glass body portion, in the present 55 instance, and C is the intervening coupling

section. The glass body section has a deep flange b and is hollow, as clearly shown in Fig. 2. The upper surface of the glass body portion is shaped so as to comfortably fit the hand and arm of the occupant of the chair, although the shape of the arm may be modified without departing from the essential features of the invention.

The coupling section C is preferably made of wood in a comparatively rough state and is secured to the base A by screws c . The glass body is secured to the wooden coupling section C by screws e . The heads of these screws are mounted in metallic washers e' , which rest in cavities b' in the glass body section B and mounted between the underside of these washers and the glass are washers f , of flexible material, preferably of leather, and mounted between the body section B and the coupling section C, 70 at the rear of the handle, is a washer g of yielding material, while at the forward end is a block E through which the screw e passes and between the upper end of this block and the glass section is a washer g' 80 and the coupling block is so proportioned that the flange b does not rest upon the metallic base A, but is clear of it, so that there is no direct contact between the metallic base and the glass body. Some suitable 85 cement, as indicated at h is preferably inserted in the space between the glass and the flange a' of the base A so as to close the crevices and to make the handle absolutely sanitary. 90

In order to hide the wooden coupling sections C, we preferably make the body portion of opaque glass or china, and if it is desirable to highly ornament the handle we may make the body portion of clear glass 95 and coat its inner surface with an opaque bronze or paint so that the bronze not only hides the coupling section, but also improves the appearance of the glass arm.

In Fig. 9, we have illustrated a modification of our invention in which the long wooden filling section C is dispensed with and two spools C', C' are used and the screws e^2 extend through the spools and are tapped into the metal of the base portion 100 of the handle. Leather or other yielding material is placed between the spool and the glass section of the handle and between the handle and the screws, and cement is placed between the flange on the base por- 110

tion and the lower edge of the glass handle, so as to prevent the accumulation of foreign matter and thus make the handle sanitary.

By the above construction the parts can be readily assembled without danger of breaking or cracking the vitreous material and the arm can be kept absolutely clean. Furthermore, the body portion being made of glass, or like material can be molded into any shape desired so as to conform to the hand and arm of the occupant of the chair.

We claim:

The combination in a chair arm, of a metallic base; a vitreous body portion mounted above the base; with a coupling section of wood located between the vitreous body section and the base and inclosed within

the body section; independent means for securing the wooden coupling section to the base; independent means for securing the vitreous body section to the coupling section; and means for preventing direct contact between the vitreous body section and the base of the coupling section.

In testimony whereof, we have signed our names to this specification, in the presence of two subscribing witnesses.

JAMES BARKER.
ALFRED BARKER.
JOSEPH P. BARKER.
